(57) CLAIM

The ornamental design for a watch, as shown and described.

DESCRIPTION

FIG. 1 is a top, right, front perspective view of a watch of our new design;

FIG. 2 is a bottom, left, back, perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines in the figures illustrate portions of the watch that form no part of the claimed design.

1 Claim, 5 Drawing Sheets
